(57) CLAIM

The ornamental design for a joint portion for a horse bit, as shown and described.

DESCRIPTION

FIG. 1 is a front elevational view of a joint portion for a horse bit shown in a first environment, the rear view being a mirror image;

FIG. 2 is a top plan view thereof, the bottom plan view being a mirror image;

FIG. 3 is a right side elevational view thereof, the left side elevational view being a mirror image;

FIG. 4 is the same front elevational view as FIG. 1, shown in a second environment, the rear being a mirror image;

FIG. 5 is a top plan view thereof, the bottom plan view being a mirror image;

FIG. 6 is a right side elevational view thereof, the left side elevational view being a mirror image;

FIG. 7 is the same front elevational view as FIG. 1, shown in a third environment, the rear being a mirror image;

FIG. 8 is a top plan view thereof; and,

FIG. 9 is a right side elevational view thereof, the left side elevational view being a mirror image.

The broken lines crossing the shafts of the joint portion in FIGS. 1, 2, 4, 5, 7 and 8 represent the bounds of the claim and all other broken lines are for illustrative purposes only. None of the broken lines form a part of the claimed design.
